(57) **CLAIM**

The ornamental design for a manifold for washing gas turbine aircraft engines, as shown.

DESCRIPTION

FIG. 1 is a rear and side perspective view of a manifold for washing gas turbine aircraft engines, showing my new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a rear elevational view thereof;

FIG. 6 is a top plan view thereof; and,

FIG. 7 is a bottom plan view thereof.
